APPARATUS FOR DRYING PAPER IN A
CONTINUOUS WEBWilliam Whiting, Holyoke, Mass., assignor to
Whiting Paper Company, Holyoke, Mass., a
corporation of Massachusetts

Application May 11, 1934, Serial No. 725,218

2 Claims. (Cl. 34—48)

This invention relates to apparatus for drying paper in a continuous web. Loft dried paper has a number of advantages in appearance and quality and many attempts have been made to secure similar appearance and quality by continuous methods and machines. In one common arrangement the web is carried successively around a series of steam heated drums and according to another method the web is formed into a traveling festoon. These expedients have not proved satisfactory in securing results equivalent to loft drying. In the case of heated drums the shrinking of the paper about the drums set up strains which are detrimental to the quality and appearance and in the festoon method uniform drying conditions are difficult if not impossible to obtain since excessive evaporation at the start reduces the temperature at that point and the humidity varies from one end of the line to the other. Also the weight of the paper in the festoon loops places an objectionable strain on the paper at the festoon bars, and the bars leave marks on the paper.

The object of the invention in general is to attain the beneficial results of loft drying or festoon drying coupled with the speed, efficiency and economy of machine drying. It is well understood that the loft drying method produces a strong, tough paper with its cockled surface characteristic of high grade paper, due to the fact that the wet paper is allowed to dry in a thoroughly relaxed condition wherein its natural shrinkage produces no strains tending to weaken the fiber such as occur in the usual machine dried product. Having this in mind I have devised an apparatus which handles the web in a continuous run as it comes from the paper making machine, and during its drying process keeps it traveling without strain or tension and so that it may be exposed with substantial uniformity on both sides to the action of the drying air. At the end of its run when the paper is completely dry and may withstand tension without injury, it may be wound up in a finished roll or subjected to further finishing processes as may be desired.

Important features of the invention to be observed are that the web of paper formed on the paper making machine is delivered therefrom in single long run through a confined and controlled drying atmosphere and with sufficient initial propelling force to keep the web traveling from one end to the other of its run. A conveyor is provided to support the paper during its run but imparts no pulling tension thereto, the paper being permitted to ride thereon in a thoroughly relaxed and unstrained condition. At the dry end of the run a tension-barrier is provided whereby the completely dried web may be pulled along after passing therethrough and which prevents said pulling tension from being transmitted backwardly to the drying web on the conveyor.

Other and further advantages will be apparent from the following specification and claims.

In the accompanying drawing which illustrates one embodiment of the invention,

Fig. 1 is a side view of a drier unit constructed according to the invention; 5

Fig. 2 is a plan view on a larger scale of a portion of the drier structure, parts being broken away;

Fig. 3 is a section substantially on line 3—3 of 10 Fig. 2;

Fig. 4 is a section substantially on line 4—4 of Fig. 2; and

Fig. 5 is a fragmentary elevational view showing an attenuation arrangement of the web supporting rolls. 15

Referring to Fig. 1, the unit comprises a short series of drying cylinders 1, an elongated drying chamber 2 provided with a blower 3 and an air conditioning unit 4. The drying cylinders 1 may 20 be of usual construction and serve to lower the initial moisture content of the paper to the point where shrinkage starts to become a troublesome factor. From the cylinders 1 the paper web enters the chamber 2, best shown in Figs. 2, 3 and 25 4. The chamber 2 is divided lengthwise by a vertical partition 5 into a walkway 6 and a main chamber or tunnel 7. Mounted in the tunnel 7 are a plurality of transverse rolls 8 adapted to support the paper web indicated at 10. The rolls 30 8 are formed of spaced narrow slats 11 and are rotatably journaled in partition 5 and a wall 12 of the chamber. The shafts 13 of the rolls extend outwardly beyond the chamber wall 12 and are provided with two pulleys 14 by means of 35 which each succeeding roll is driven from the preceding roll by belts 15, the initial roll being driven from a motor 16 by a belt 17. The speed of the motor is controlled by a control unit indicated at 18 which may be of any conventional 40 construction. The surface speed of rolls 8 is made such as to "float" the web forward at the initial speed imparted to it by the cylinders 1, so that no drag or strain is placed on the web in its passage through the tunnel and the paper while 45 drying is substantially as free from restraint as is the case in loft drying. In order to adjust the speed of the rolls 8 to accommodate the shrinkage of the web as it dries, means are provided at intervals for modifying the speed of the succeeding rolls and in the embodiment shown this is accomplished by substituting cone pulleys 20 for the outer pulleys 14 of two adjacent rolls 8. The shaft of one of the adjacent pair of rolls carrying the cone pulleys is made hollow to receive a 55 shaft 22 passing through the pulley and having its end beyond the pulley screw threaded and journaled in a bearing 23 formed on a bracket 25 secured to the wall 12. A belt shifter 26 is threaded on the shaft 22 and engages the belt 28 con- 60

necting the cone pulleys. The opposite end of shaft 22 is provided with a handwheel 30 accessible from the walkway 6 by which the belt 28 may be shifted to adjust the speed of rolls 8. 5 In order that the attendant may inspect the traveling web windows 31 are provided at intervals in the tunnel wall. A transverse metal partition 35 is positioned across the tunnel forming with the top of the chamber an air duct 36 10 spaced above the traveling web. Spaced transverse metal partitions 37 and 38 form a similar air duct 40 spaced below the traveling web. Partition 38 and the floor of the chamber form a return duct 41 as later described. Air ducts 36 15 and 40 are closed at their ends adjacent the forward end of the tunnel as indicated respectively at 42 and 43 in Fig. 1. Air is forced into the ducts at a point adjacent their rear ends by a blower 44 of any suitable type, driven by a motor 45. As shown in Fig. 3 the blower discharges 20 through branch ducts 46 and 47 connecting respectively with ducts 36 and 40.

As best shown in Figs. 3 and 4 the partitions 35 25 and 37 are provided with a plurality of apertures 50 formed by making U-shaped cuts in the partitions, the metal within the cuts being bent outwardly at an angle of substantially 45° to form deflectors 51 extending into the air ducts in the path of the air flow and directing the air into the 30 tunnel against the moving web of paper. As shown in Fig. 1 the air passing into the tunnel through the apertures 50 is discharged at the end of the tunnel into the return duct 41 by which it is returned to the blower through duct 53. Fresh 35 air is also supplied to the blower through an opening 54 formed in a casing 55 in which is positioned an air washer 56, an air filter 57 and a heater 58, the latter being supplied with steam through a pipe 59 having a valve 60 by means of 40 which the temperature of the air may be controlled.

If the fresh air entering the air system is very dry the moisture expelled from the paper tends to bring the circulating air to the desired humidity. 45 An air outlet 61 provided with an exhaust fan 62 and controlled by a damper 63 permits discharge of the moisture laden air at a rate such that in combination with the dry air entering through opening 54 the humidity of the air circulating in 50 the tunnel may be maintained at the desired humidity as indicated by wet bulbs (not shown) positioned at convenient points in the tunnel and viewable through the windows 31.

The paper web is discharged from the tunnel 55 over a turtle back 65 through a tension control device 66 to a power driven wind up 67 of any suitable kind, the tension device being adjusted to prevent the wind up from exerting drag on the paper web in the tunnel.

60 It will be seen that the web moves continuously through the tunnel without substantial tension and substantially free from restraint as it dries. The narrow slats 11 which form the surface of the rolls move as previously pointed out at substantially the surface speed of the paper and no marking or marring of the surface of the web takes place as it advances through the tunnel.

65 In Fig. 5 is shown an alternative arrangement in which the rolls 8 are not positively driven but are placed on an incline so that the paper advances freely by gravity under the initial movement imparted by the cylinders 1.

I claim:

1. In an apparatus for drying material in a continuous running web, in combination, a substantially straight line drying tunnel, a plurality of drying cylinders positioned at the inlet end of the tunnel between which the web passes and by which the moisture content of the web is reduced to a point short of where substantial shrinkage occurs, said cylinders advancing the web into the drying tunnel, a web conveyor in the 10 drying tunnel which receives the web from said cylinders, said conveyor comprising a series of slatted open rolls of relatively large diameter, the rolls being spaced apart so that the traveling web sags between adjacent rolls and the shape of the 15 portion of the web supported by each roll conforms to the curved surface of a section of a cylinder formed by passing a plane through each cylindrical roll parallel to its longitudinal axis, means extraneous of said web for driving the supporting rolls, other means for adjusting the speed of certain rolls with respect to other rolls so that all the rolls are driven at speed regulated to the shrinkage of the web and the initial speed imparted to the web by the drying cylinders whereby the web is advanced through the tunnel substantially without tension, means for causing currents of air to flow in said tunnel along both the upper and lower sides of the traveling web, and means to direct said air currents against the web, with a component of motion in the direction of web travel, throughout the length of the 20 tunnel.

2. In an apparatus for drying material in a continuous running web, in combination, a substantially straight line drying tunnel, a plurality of drying cylinders positioned at the inlet end of the tunnel between which the web passes and by which the moisture content of the web is reduced to a point short of where substantial shrinkage occurs, said cylinders advancing the web into the drying tunnel, a web conveyor in the 25 drying tunnel which receives the web from said cylinders, said conveyor comprising a series of slatted open rolls of relatively large diameter, the rolls being spaced apart so that the traveling web sags between adjacent rolls and the shape of the portion of the web supported by each roll conforms to the curved surface of a section of a cylinder formed by passing a plane through each 30 cylindrical roll parallel to its longitudinal axis, means extraneous of said web for driving the supporting rolls, other means for adjusting the speed of certain rolls with respect to other rolls so that all the rolls are driven at speed regulated to the shrinkage of the web and the initial speed imparted to the web by the drying cylinders whereby the web is advanced through the tunnel substantially without tension, means for causing currents of air to flow in said tunnel along both the upper and lower sides of the traveling web, and means to direct said air currents against the web, with a component of motion in the direction of web travel, throughout the length of the 35 tunnel.

WILLIAM WHITING.
